CLAIM

The ornamental design for a wallet for card, cash and cellphone, as shown and described.

DESCRIPTION

FIG. 1 is a perspective view of a wallet for card, cash and cellphone showing my new design in a folded position;

FIG. 2 is a front elevation view of FIG. 1;

FIG. 3 is a rear elevation view of FIG. 1;

FIG. 4 is a right side elevation view of FIG. 1;

FIG. 5 is a left side elevation view of FIG. 1;

FIG. 6 is a top plan view of FIG. 1;

FIG. 7 is a bottom plan view of FIG. 1;

FIG. 8 is a front elevation view thereof, showing my new design in a unfolded position;

FIG. 9 is an exploded view of FIG. 8;

FIG. 10 is another exploded view of FIG. 8, showing the rear view of the phone case;

FIG. 11 is a perspective view thereof, showing my new design in a unfolded position;

FIG. 12 is a perspective view thereof, showing my new design in a unfolded position; and,

FIG. 13 is a perspective view thereof, showing my new design in a unfolded position.

The broken lines in the figures depict stitching lines which form no part of the claimed design.
